BRACELET.

No. 808,322.

Specification of Letters Patent.

Patented Dec. 26, 1905.

Application filed May 2, 1905. Serial No. 258,453.

To all whom it may concern:

Be it known that I, WALFRID WALLENTHIN, a citizen of the United States, residing at Attleboro, in the county of Bristol and State of Massachusetts, have invented a new and useful Improvement in Bracelets, of which the following is a specification.

This invention has reference to an improvement in bracelets, and more particularly to an improvement in the means for pivotally securing the two halves of a bracelet together.

The object of my invention is to improve the construction of bracelets, thereby providing a bracelet with a pivot-hinge constructed so as to separate the two halves of a bracelet when the bracelet is opened and to draw the halves of the bracelet together when the bracelet is closed.

A further object of my invention is to provide a two-part bracelet with a pivot-hinge having stops to limit the opening and closing of the bracelet.

My invention consists in the peculiar and novel construction of a two-part bracelet, each semicircular part constructed from a tubular bar and a pivot-hinge consisting of two members shaped to fit in the adjacent ends of the bracelet, one member having a projecting lug and the other member having a recess for the lug, the end walls of the recess acting as a stop for the lug to limit the opening and closing of the bracelet, a pivot pin or pintle rigidly secured in one member and screw-threaded through the other member, whereby the opening of the bracelet separates the members of the pivot-hinge and the bracelet and the closing of the bracelet draws the members of the hinge and bracelet firmly together, and other details of construction, as will be more fully set forth herein-after.

Figure 1 is a side view of my improved bracelet, showing the bracelet in the closed position. Fig. 2 is an edge view of the bracelet, showing the bracelet in the closed position in full lines and in the open position in broken lines. Fig. 3 is an enlarged detail sectional view showing the pivot-hinge of the bracelet. Fig. 4 is an enlarged sectional view taken on line X X of Fig. 3 through the pivot-hinge of the bracelet. Fig. 5 is an enlarged transverse sectional view through the pivot-hinge, taken on line Y Y of Fig. 1;

and Fig. 6 is an enlarged detail sectional view of the snap, taken on line Z Z of Fig. 1. 55

In the drawings, *c* indicates one semicircular half of the bracelet, *d* the other semicircular half, and *e* the pivot-hinge of the bracelet.

The semicircular halves *c* and *d* of the bracelet are constructed from a tubular bar which is circular in cross-section. The ends *c'* and *d'* are cut square across and coincide when the bracelet is closed. The ends *c*² and *d*² are cut at an angle, as shown in Fig. 6, and a plug *d*³ is secured in the end *d*² of the semicircular half *d* by solder or other means. This plug *d*³ extends slightly above the end *d*² and forms a snap by snapping into the open end *c*² of the semicircular half *c* when the bracelet is closed, thus holding the bracelet in the closed position. 6c 65 70

The pivot-hinge *e* consists of a member *e'*, shaped to fit in the end *c'* of the bracelet and constructed to have the central hole *e*² and the off-center lug *e*³, a member *e*⁴, shaped to fit into the end *d'* of the bracelet and having the screw-threaded central hole *e*⁵ and the off-center recess *e*⁶, with the end walls *e*⁷ and *e*⁸ forming a stop for the lug *e*³, and the pin *e*⁹, 80 having the screw-threaded portion *e*¹⁰ adapted to screw into the screw-threaded hole *e*⁵ in the member *e*⁴, and the reduced portion *e*¹¹, adapted to enter the hole *e*² in the member *e'*, as shown in Fig. 4. 85

The pivot-hinge *e* is assembled by first screwing the screw-threaded portion *e*¹⁰ of the pin *e*⁹ into the screw-threaded hole *e*⁵ in the member *e*⁴ its entire length. The member *e'* is now placed into position, with the reduced portion *e*¹¹ of the pin extending through the hole *e*², and the lug *e*³ extending into the recess *e*⁶ in the member and the whole secured together by upsetting the end *e*¹² of the pin onto the end of the member *e'*, as shown 95 in Fig. 4. The members *e'* and *e*⁴ are now secured in the ends *c'* and *d'* of the bracelet by solder or other means. 90

In opening the bracelet the ends *c*² and *d*² are forced apart. The screw-threaded portion *e*¹⁰ of the pin *e*⁹ unscrewing in the member *e*⁴ separates the members of the hinge and the halves of the bracelet, and the end wall *e*⁸ of the recess *e*⁶ acts as a stop for the lug *e*³ and limits the opening movement of the bracelet. 105 When the bracelet is closed, the screw-thread-

ed portion e^{10} of the pin screwing into the member e^4 draws the members of the hinge and the halves of the bracelet firmly together. The end wall e^7 of the recess e^6 acts as a stop 5 for the lug e^3 to limit the closing movement of the bracelet, and the end e^2 of the half c riding up the inclined surface of the plug d^3 snaps over the protruding end of the plug and holds the bracelet in the closed position, as 10 shown in Fig. 6.

It is evident that the two halves c and d of the bracelet could be oval in cross-section and that the bracelet could have any design or configuration desired without materially affecting 15 the spirit of my invention.

Having thus described my invention, I claim as new and desire to secure by Letters Patent—

1. A bracelet the body of which consists of two semicircular halves, a pivot-hinge constructed of a member having a central hole and an off-center lug, a member having a screw-threaded central hole and an off-center recess the end walls of which form stops for the lug, and a pin having a screw-threaded 20 portion adapted to enter the screw-threaded central hole in one member and a reduced portion adapted to enter the central hole in the other member, means for securing the members together, and means for securing the 25 pivot-hinge in the adjacent ends of the bracelet, whereby the pivoted ends of the two halves of the bracelet separate when the bracelet is 30 opened, are drawn firmly together when the bracelet is closed, and the opening and closing movements of the bracelet are limited, as described.

2. A bracelet the body of which is formed of two semicircular halves c and d secured together by a pivot-hinge, consisting of a member e^1 having the central hole e^2 and the off-center lug e^3 , a member e^4 having the screw-threaded central hole e^5 and the off-center recess e^6 with the end walls e^7 and e^8 forming 35 stops for the lug e^3 , and a pin e^9 having the

screw-threaded portion e^{10} adapted to screw 45 into the hole e^5 in the member e^4 , and the reduced portion e^{11} adapted to enter the hole e^2 in the member e^1 , and secured by upsetting the end of the reduced portion e^{11} onto the end of the member e^1 , whereby the opening of the hinge will separate the members of the hinge, the closing of the hinge will draw the members of the hinge firmly together, and the opening and closing movements of the hinge are limited, as described. 50

3. In a bracelet, the combination of the tubular semicircular halves c and d the ends c' and d' of which are cut square across and the ends c^2 and d^2 at an angle, of a pivot-hinge e consisting of a member e^1 shaped to fit in the end c' of the bracelet and having the central hole e^2 and the off-center lug e^3 , a member e^4 shaped to fit in the end d' of the bracelet and having the screw-threaded central hole e^5 , the off-center recess e^6 with the end walls e^7 and e^8 forming stops for the lug e^3 , and a pin e^9 having the screw-threaded portion e^{10} adapted to screw into the hole e^5 in the member e^4 , and the reduced portion e^{11} adapted to enter the hole e^2 in the member e^1 and secured in the member by upsetting the end onto the end of the member e^1 , means for securing the pivot-hinge in the ends c' and d' of the bracelet, whereby the opening of the bracelet will separate the pivoted ends of the two halves c and d of the bracelet, the closing of the bracelet will draw the halves of the bracelet firmly together, and the opening and closing movements of the bracelet limited, and means for holding the bracelet in the closed position, as 80 described. 75

In testimony whereof I have signed my name to this specification in presence of two witnesses here subscribed.

WALFRID WALLENTHIN.
